UNITED STATES PATENT OFFICE.

WILLIAM S. VAN SANT, OF FRUITVALE, CALIFORNIA, ASSIGNOR OF ONE-THIRD TO EVERETT N. MCCUTCHEON AND ONE-THIRD TO ELIJAH M. HIATT, OF OAKLAND, CALIFORNIA.

PAPER-CONE-WRAPPING MACHINE AND THE PRODUCT OBTAINED THEREBY.

Application filed June 16, 1920, Serial No. 389,350. Renewed June 28, 1922. Serial No. 571,472.

To all whom it may concern:

Be it known that I, WILLIAM S. VAN SANT, a citizen of the United States, residing at Fruitvale, in the county of Alameda 5 and State of California, have invented a new and useful Improvement in Paper-Cone-Wrapping Machines and the Product Obtained Thereby, of which the following is a specification.

This invention relates to a machine for the manufacture of paper containers, and especially to a machine which is adapted to form and wrap cone-shaped containers.

The invention also relates to the product obtained, to-wit, a cone-shaped paper container folded or wrapped in such a manner that a water or liquid tight container is produced.

One of the objects of the present invention is to provide a simple, substantial and cheaply manufactured paperwrapping and forming machine which is especially adapted for forming and wrapping cone-shaped containers, and simultaneously adapted to trim 25 the paper or stock from which the container is formed so as to produce an even annular edge around the upper open end of the cone.

Another object of the invention is to provide a wrapping or forming machine of the 30 character described by which a water or liquid tight joint or fold may be formed at the lower or pointed end of a paper cone, said fold also serving to reinforce and strengthen the pointed end of the cone.

Another object of the invention is to provide a yieldable paper feeding table for the reception of the stock or sheets from which the cones are formed, and to so position the feeding table that the sheets may be easily 40 delivered one by one to the wrapping mechanism.

Another object of the invention is to provide means for rotating the wrapping mechanism while each cone is formed, and in conjunction therewith to provide means for ejecting the cones one by one when formed.

Further objects will hereinafter appear.

The invention consists of the parts and the construction, combination and arrange-

ment of parts as hereinafter more fully described and claimed, having reference to the accompanying drawings, in which—

Fig. 1 is a plan view of the cone forming and wrapping machine.

Fig. 2 is a front view of the wrapping cone.

Fig. 3 is a cross section on line 3—3, Fig. 1.

Fig. 4 is a cross section on line 4—4, Fig. 1.

Fig. 5 is a longitudinal section on line 5—5, Fig. 1.

Fig. 6 is a detail plan view of the wrapping cone.

Fig. 7 is a plan view of the paper blank 65 from which the cone is formed.

Fig. 8 is a detail view showing the manner in which the cone is formed during the wrapping operation.

Fig. 9 is a detail view showing the completed cone.

Fig. 10 is a detail view showing the reinforcing fold formed at the pointed end of the cone during the wrapping operation.

Referring to the drawings in detail, A 75 indicates a base member of suitable construction upon which is secured a pair of bearing members 2 and 3. Journalled in said bearing members is a hollow shaft 4, and secured on said shaft is a cone shaped wrapping member 5. Also secured on the shaft or formed integral with the cone, as indicated at 6, is a head member. This member is spaced with relation to the base portion of the cone and an annular channel 7 is in 85 this manner formed for the reception of a trimming knife 8, the function of which will hereinafter be described. Extending through the hollow shaft 4 and the cone member 5, and adapted to turn in unison 90 with the shaft is a rod 9. Secured on the rod is a collar 10, and interposed between the collar and the head member 6 is a spring 11. Formed on one end of the rod 9 is a striking plate 12, and secured on the outer 95 end of the rod is a pointed section 14, which forms a part of the main wrapping cone 5, that is the cone 5 is made in two sections as

indicated at 5 and 14, the section 5 representing the main portion of the cone, and the section 14, the pointed end or the apex of the cone. The section 14 is provided for the purpose of ejecting paper cones when completed. It is therefore capable of separation or longitudinal movement with relation to the main cone section 5, by means of the rod 9 and the striking plate 12, that is present 5 sure exerted on the plate 12 will impart longitudinal movement to the rod 9 and the section 14 carried thereby, this longitudinal movement being sufficient to eject the cones one by one when completed, the spring 11 serving the function of returning the rod 9 and the section 14 to normal position as shown in Figs. 1 and 5. The head member 6 and the cone sections 5 and 14 are channeled as indicated at 15, the channels formed 10 in the respective sections being aligned to form a continuous channel for the reception of one edge of the paper blank as shown in Fig. 1 when the wrapping operation is to be started. With the paper inserted in the channel, it is only necessary to turn the cone approximately two revolutions. This is accomplished in the present instance by 15 manual operation through the medium of a hand crank 16. Turning movement imparted to the cone causes the paper to wrap itself about the cone and as a rectangular blank is employed, it is obvious that the upper edge will necessarily have to be trimmed to form a smooth annular edge. This is accomplished by providing the trimming knife 8. 20 This knife is supported by an arm 17, hingedly secured to the base plate A as at 18. The trimming blade projects into the annular groove 7, being held therein by means of a spring 19. The trimming operation is clearly shown in Fig. 6, and the rectangular blank when completely trimmed 25 will assume the shape shown in Fig. 7.

The paper blanks in actual operation are placed on a receiving pan B and they are transferred from this receiving pan to a feeding table generally indicated at C, one-half of each sheet having paste applied thereto in any suitable manner before delivery to the feeding table. The feeding table is hingedly secured at one side as at 19 to the base plate and the opposite side is resiliently supported by means of a spring 20. This side of the feeding table is extended 30 as at 21 to form a handle or projection, by which the table may be depressed, and the upper end of the table or that passing underneath the wrapping cone is slightly concave as at 22, (see Fig. 4.) to frictionally engage the exterior surface of the wrapping cone, that is a paper blank having paste applied thereto, as shown at 23, is placed on the table in such a manner that one edge thereof enters the channel 15 formed in the wrap-

ping cone. Rotary movement is then transmitted to the cone by means of the hand crank 16. In this manner causing the paper to wrap itself about the cone. The concave portion of the table, indicated at 22, frictionally engages the surface of the cone and thereby causes the paper to be tightly wrapped about the same. The trimming knife or blade 8 simultaneously engages the outer uneven edge of the paper blank and proper trimming thereof is in this manner accomplished. It requires approximately two revolutions to complete the operation and as one-half of the sheet or blank has paste applied thereto, it is obvious that unwrapping of the paper cone will not take place once the wrapping operation has been completed. The paper is in fact so tightly wrapped about the cone that the ejector 14 must be employed to remove the same.

The present invention is not only drawn to cover the mechanism employed, but also the product obtained, in as much as the cone when completed presents a paper container which is not only decidedly stronger than paper cones heretofore produced, but also liquid tight. These results are obtained in the following manner:

By referring to Fig. 1, it will be seen that the paper blank when inserted in the channel 15 is a little longer than twice the length of the wrapping cone, that is the cone merely reaches the dotted line indicated at 25, the center line of the blank being indicated at 26. The paper when wrapped is therefore started slightly off center and causes a lateral fold 27 to be produced as shown in Figs. 6 and 10. This fold not only reinforces and strengthens the point of the cone, but it also produces a water tight joint, a feature which is decidedly desirable as it permits the paper cones to be employed for a variety of uses, for instance as drinking cups or containers for ice cream, and a great variety of other articles.

The machine here shown is decidedly simple and substantial in construction. The feeding table is arranged on an angle with relation to the longitudinal axis of the wrapping cone, the angular relation being equal to the inclined exterior surface of the wrapping cone and running parallel therewith. The paper blanks delivered thereto, one by one, are therefore readily inserted in the feeding slot 15 of the cone and are adjusted and held in position by means of a guide 28.

The paste may be applied in any suitable manner and as the paper is snugly forced against the exterior surface of the wrapping cone by the feed table extension 22, it can be seen that a uniform and perfect product will be obtained.

The trimming knife employed may be an ordinary safety razor blade or the like. This

blade may be readily removed by detaching the spring 19 and swinging the arm 17 about the hinge support 18. No time should therefore be lost when the trimming blade becomes dull as a new and sharp blade may be readily inserted.

While the present machine shown is equipped with a hand crank, it is obvious that a power drive may be employed. Similarly that various changes in design and construction may be resorted to within the scope of the appended claims, also that the materials and finish of the several parts employed may be such as the experience and judgment of the manufacturer may dictate or varying uses may demand.

Having thus described my invention, what I claim and desire to secure by Letters Patent is—

1. In a wrapping machine of the character described a shaft, a cone-shaped member carried thereby, said cone shaped member having a channel formed therein which extends from the apex to the base of the cone, means for rotating the shaft and cone carried thereby, an annular groove formed in the cone adjacent the base thereof, and a trimming knife projecting therein.

2. In a wrapping machine of the character described a shaft, a cone-shaped member carried thereby, said cone shaped member having a channel formed therein which extends from the apex to the base of the cone, means for rotating the shaft and cone carried thereby, a head member on the shaft adjacent the base of the cone and interspaced with relation thereto to form an annular channel, a paper trimming blade extending into the annular channel, a hinge support for the blade, and spring actuated means for retaining the blade in the channel.

3. In a wrapping machine of the character described the combination with the wrapping cone, of a paper feeding table positioned adjacent the cone and on an angle with relation to the longitudinal axis of the cone, said angle being substantially the same as the inclined exterior surface of the cone, a hinge support for one side of the table and a resilient support for the opposite side of the table.

4. In a wrapping machine of the character described the combination with the wrapping cone, of a paper feeding table positioned adjacent the cone and on an angle with relation to the longitudinal axis of the cone, said angle being substantially the same as the inclined exterior surface of the cone, a hinge support for one side of the table, a resilient support for the opposite side of the table, and a projection on the table frictionally engaging the exterior surface of the wrapping cone.

5. In a wrapping machine of the character described a cone shaped wrapping member, said wrapping member consisting of two separable sections, a hollow shaft supporting one of the sections, a rod extending therethrough and supporting the other section, means for rotating the shaft and rod in unison, and means permitting longitudinal movement of the rod and the cone section carried thereby to longitudinally separate the cone sections.

6. In a wrapping machine of the character described a cone shaped wrapping member, consisting of two sections, a common support for said sections, and means permitting longitudinal movement of one section with relation to the other.

7. In a wrapping machine of the character described the combination with the wrapping cone and a shaft whereby it is supported and rotated, of a head member on the shaft adjacent the base of the cone, said cone and head member being interspaced to form an annular channel, a trimming-knife projecting into the channel and a spring for retaining the knife in the channel.

8. In a wrapping machine of the character described the combination with the wrapping cone of a paper feeding table positioned adjacent one side thereof, a hinge support for one side of the table, a resilient support for the opposite side of the table, and an extension on the table passing under the cone and frictionally engaging the same.

9. In a wrapping machine of the character described the combination with the wrapping cone of a paper feeding table positioned adjacent one side thereof, a hinge support for one side of the table, a resilient support for the opposite side of the table, an extension on the table passing under the cone and frictionally engaging the same, a guide member on one end of the table adjacent the base of the cone, a channel formed in the cone and extending from end to end thereof, said channel adapted to receive one edge of a paper blank, and manually actuated means for depressing one side of the table when completed cones are to be removed.

10. In a wrapping machine of the character described the combination with the wrapping cone of a paper feeding table positioned adjacent one side thereof, a hinge support for one side of the table, a resilient support for the opposite side of the table, an extension on the table passing under the cone and frictionally engaging the same, a guide member on one end of the table adjacent the base of the cone, a channel formed in the cone and extending from end to end thereof, said channel adapted to receive one edge of a paper blank, manually actuated means for depressing one side of the table, and other means for imparting a longitudi-

nal movement to each paper cone when exterior surface of the cone wrapping member is wrapped to free it with relation to the wrapping cone.

11. In a wrapping machine a cone shaped wrapping member, a support and turning means therefor, and a paper feeding table having a curved portion in which the wrapping cone is operatively disposed, said curved portion being complementary to the

In testimony whereof I have hereunto set my hand in the presence of two subscribing witnesses.
